UNITED STATES PATENT OFFICE.

OLIVER M. BABCOCK, OF CHICAGO, ILLINOIS, ASSIGNOR TO WIREBOUNDS PATENTS COMPANY, OF KITTERY, MAINE, A CORPORATION OF MAINE.

BOX.

1,247,359.

Specification of Letters Patent. Patented Nov. 20, 1917.

Application filed September 18, 1914. Serial No. 862,411.

To all whom it may concern:

Be it known that I, OLIVER M. BABCOCK, a citizen of the United States, residing in Chicago, Cook county, Illinois, have invented an Improvement in Boxes, of which the following description, in connection with the accompanying drawings, is a specification, like characters on the drawings representing like parts.

10 This invention relates to boxes and pertains more particularly to boxes comprising cleats and sheet metal sides.

Among other objects, the invention is intended to provide a box which shall be very strong and durable and economical to manufacture. The invention comprises, also, a method of making boxes.

The character of the invention may be readily understood by reference to the accompanying drawings showing an illustrative form of box blank and box.

In the drawings,

Figure 1 is a side or edge view of the illustrative box blank;

25 Fig. 2 is a plan view of the blank shown in Fig. 1;

Fig. 3 is a perspective of the finished box made from the blank shown in Figs. 1 and 2; and

30 Fig. 4 is a detail fragmentary section on the plane of line 4—4 of Fig. 3, the plane being parallel with the cleats but with certain parts shown in another position.

The illustrative blank comprises cleats 6 and 7 and a preferably continuous metal side sheet 8 secured to the cleats in any practicable manner as, for instance, by staples 9, 9 driven through the sheet metal sides and into the cleats.

40 As shown in Fig. 2 there are four cleats, and the extremities of the metal sheet 8 are appropriately cut to form connecting tabs 11, 11 and 12, 12.

As shown in Fig. 1, the adjacent ends of the cleats 6 and 7 are spaced apart a distance substantially equal to the combined thicknesses of the cleats 6 and 7 so that when the blank is folded into box form as shown in Fig. 3, that part of the side material which 50 in the blank intervenes between the cleat ends, will, in the folded box, extend across the cleat ends and constitute a side of the box. The cleats in the illustrative form of box are arranged to contact lengthwise and 55 constitute the closures at the ends of the

box. A metal side sheet 8 has end margins 15 and 16 which overlap as shown in Fig. 3, when the box is closed; and tabs 11 and 12 are arranged to be bent out from the respective end margins 15 and 16 so that said 60 tabs will contact with each other. Also, the tabs may be provided with means for securing them together; for example, they may have holes to receive eyelets or rivets such as rivets 18, 18.

65 There are many advantages in a box of the general character described. The strength and durability of the sheet metal sides are combined with the stiffness of preferably wooden cleats, so that the box is extremely strong and durable.

70 It is to be understood that the invention is not limited to the specific construction and organization described above nor to the particular method described for illustration. On the contrary, the invention may be variously embodied in boxes and other receptacles (all of which are intended to be included within the meaning of the word "box" as used in the claims) and various 75 modifications may be made in the described method.

Claims:

1. A box comprising sides formed of a continuous folded strip of sheet metal and 85 wooden end pieces secured to said sides and maintaining them in box-like form, said end pieces comprising a plurality of separable parts secured to separate side-forming portions of said strip.

90 2. A box comprising sides formed of a continuous folded strip of sheet metal and wooden cleats secured to the strip and mating to close the ends of the box and to retain the sides in box-like form.

95 3. A box comprising, in combination, a group of cleats at each end of the box including two cleats substantially contacting lengthwise; sheet metal side material at opposite sides of said cleats; and means to secure the parts together.

100 4. A box comprising, in combination, a group of cleats at each end of the box, including two cleats substantially contacting lengthwise; sheet metal side material folded transversely of the ends of said cleats, and along the sides thereof to form the box sides; and means to secure the parts together.

105 5. A box having end closures and sides

formed from a sheet of stiff, bendable material encircling the ends and lapping on itself, said edges being slit to provide tongues which are secured together in abutting contact.

6. A method of making boxes which comprises assembling separate cleats with sheet metal side material; and securing the sheet metal side material to the cleats placed end to end so as to connect said cleats flexibly by the sheet metal side material.

7. A method of making boxes which comprises assembling a plurality of rows of cleats, the cleats in each row being alined end to end, and a substantially continuous sheet of metal side material bridging the intervals between said cleats, and securing the cleats and sheet metal side material together to form a foldable blank.

8. A method of making boxes which comprises assembling sheet metal side material with cleats having their ends spaced apart a distance substantially equal to the combined widths of said cleats and securing the sheet metal side material to the cleats and across said interval to connect the cleats flexibly by said sheet material to form a foldable box blank with the cleats arranged substantially to contact lengthwise when the blank is folded.

In testimony whereof, I have signed my name to this specification, in the presence of two subscribing witnesses.

OLIVER M. BABCOCK.
